(57) CLAIM

The ornamental design for a mirror, as shown and described.

DESCRIPTION

FIG. 1 is a perspective view of a mirror according to an embodiment of the invention.

FIG. 2 is a side view of a mirror according to an embodiment of the invention, the view from the opposite side being a mirror-image thereto.

FIG. 3 is a top view of a mirror according to an embodiment of the invention; and,

FIG. 4 is a front view of a mirror according to an embodiment of the invention.

The broken lines on the frame surrounding the glass mirror surface form no part of the claimed invention. The surfaces are lined for color. The vertical-horizontal cross-hatching is indicative of a dark near black finish. The cross-hatching is only shown on portions of the surfaces for clarity but should be considered to extend the entirety of the mirror with the exception of central glass surface having the diagonal lines.

The claimed design does not include any depth for the ornamental details shown within the perimeter moldings.

All of the material from U.S. Pat. No. D557,905 which is essential to the claimed design is included herein. Any material in U.S. Pat. No. D557,905 which is not present herein form no part of the claimed design.
